UNITED STATES PATENT OFFICE.

JOSEPH E. STEELE, OF COLUMBUS, OHIO.

ELECTRICALLY-OPERATED RAILWAY-CROSSING ALARM.

SPECIFICATION forming part of Letters Patent No. 631,134, dated August 15, 1899.

Application filed May 8, 1899. Serial No. 715,924. (No model.)

To all whom it may concern:

Be it known that I, JOSEPH E. STEELE, a citizen of the United States, residing at Columbus, in the county of Franklin and State of Ohio, have invented a certain new and useful Improvement in Electrically-Operated Railway-Crossing Alarms, of which the following is a specification.

My invention relates to the improvement of railway-crossing signals, and has particular relation to that class of signals which are operated by electricity.

The objects of my invention are to provide a simple, reliable, and effective bell-ringing mechanism of improved construction whereby the ringing of an alarm-bell will result from a train approaching a crossing in either direction and whereby the ringing of said alarm-bell will be prevented when the train is leaving the crossing. These objects I accomplish in the manner illustrated in the accompanying drawing, in which is illustrated a plan view of a portion of a railway-track, showing in connection therewith the apparatus which I employ in carrying out my invention.

Similar numerals and letters refer to similar parts throughout the drawing.

1 and 2 represent, respectively, the lines of track-rails of an ordinary railway, those sections of track-rails which intersect a road-crossing and which are indicated at 3 and 4 being insulated at 5 from the adjoining sections and those adjoining sections which are indicated at 6 and 7 and 8 and 9 are insulated at 10 from the outer sections.

In carrying out my invention I employ at a suitable point two relays 11 and 12. Of the relay 11, 13 represents a horizontal magnet, and 14 a vertical relay armature-bar which is pivoted at its lower end and which is adapted to extend in front of the magnet 13, and 15 and 16 represent, respectively, the oppositely-located contact-arms, between the inner ends 45 of which the upper end portion of said relay-bar 14 extends. As indicated at 17, I employ a spring which normally retains the bar 14 in contact with the outer contact-arm 15. Of the relay 12, 18 represents the magnet-coil, 50 19 the pivoted armature-bar, and 20 and 21 the contact bars or arms, which correspond with the bars or arms 15 and 16, with the ex-

ception that said arm 21 is insulated or of non-conducting material. Through the medium of a spring 22 the armature-bar 19 is 55 normally held in contact with said insulated arm 21.

As indicated at *a a*, the track-sections 6 and 8 and 7 and 9 are electrically connected through the medium of wires. From the track-section 6 runs a wire line *b*, which being intersected by a battery *b'* is connected with the magnet-coil 18. Through the medium of a wire line *c* a connection is produced between the track-section 7 and the relay-bar 14. 65

d represents a wire line which being intersected by a battery *d'* connects the track-section 3 with the magnet-coil 13.

e represents a wire line which connects the track-section 4 and magnet-coil 13, and *f* is 70 a short wire line which forms a connection between the wires *e* and *b*.

23 represents a suitable form of electric bell, with the contact-posts 24 and 25 of which are connected wires *g* and *h*, the latter being 75 intersected by a battery *i* and leading to the armature-bar 19 and the former leading to the contact-arm 20.

k represents a wire which connects the contact-arm 15 with the magnet 18, and *m* represents a similar connection between the contact-arm 16 and point on the wire *d* adjacent to the magnet 13. 80

In order to better illustrate the operation of my device, I have shown in plan on the railway-track a car-truck axle and wheels, the same being indicated at 26, and in order to make clear the operation of my improved signal-bell we will assume that a train is approaching in the direction of the arrow. The 85 car-wheels having reached the position indicated in the drawing—that is, bearing upon the track-sections 6 and 7—it is obvious that through the medium of the wires *b*, *c*, and *k* and their connections heretofore described 90 an electric circuit will be established, which will result in magnetizing the coil 18 and in drawing the armature-bar 19 into contact with said magnet and into contact with the contact-arm 20. Through this operation it will 95 readily be seen that a circuit will be established through the battery *i* and bell 23, resulting in ringing the latter, so long as the car axles and wheels are producing a connec- 100

tion between the track-sections 6 and 7. We will assume now that the car-wheels have moved over onto the track-rail sections 3 and 4, which are at the crossing. It is obvious that when said sections 3 and 4 are thus connected a circuit is established through the wire *d*, battery *d'*, wire *e*, and magnet 13, which results through the magnetizing of the latter in the armature-bar 14 being drawn into contact with said magnet and into contact with the arm 16, thereby cutting out connection between said armature-bar and the wire *k* and breaking the circuit which leads through the bell and stopping the ringing of the latter. The car wheels and axles having passed the section 3 and connected the rail-sections 8 and 9, a circuit is again established through the wires *b* and *c*, the former, however, connecting through the medium of the short wire *f* with the wire *e* and which, taken in connection with the contact of the bar 14 and arm 16 and the connection of the latter with the wire *d*, results in retaining the coil 13 magnetized and the broken circuit through the bell continued so long as the cars are on said track-sections 8 and 9 and moving away from the crossing.

In view of the fact that a train approaching the crossing in the opposite direction from that indicated by the arrow would result in an operation similar to that heretofore described it is not deemed necessary to illustrate this operation by further explanation.

From the construction and operation described it will readily be seen that the connections of the various insulated rail-sections through the relays, batteries, and bell are so arranged as to insure a ringing of the alarm-bell as the train approaches a crossing and to

further insure a discontinuance of such ringing when the train is on or passed the crossing. It will also be observed that the mechanism which I employ for accomplishing these objects is simple, comparatively inexpensive, and positive in its operation.

Having now fully described my invention, what I claim, and desire to secure by Letters Patent, is—

In an electrically-operated railway-crossing alarm, the combination with a railway-track comprising track-sections 6 and 7, 3 and 4 and 8 and 9, said sections 6 and 7 and 8 and 9 being electrically connected and insulated from said sections 3 and 4, relays 11 and 12 each comprising a magnet, oppositely-located contact-arms and a pivoted armature-bar normally in contact with the outer contact-arm and an electric alarm-bell, of a connection *b* connecting the rail-section 6 through a battery with the magnet of the relay 12, a connection *c* between the section 7 and the armature-bar of the relay 11, a connection *d* through a battery between the rail-section 3, the magnet and one contact-arm of the relay 11, a connection *e* between the rail-section 4 and the magnet of the relay 11, a connection *f* between the lines *b* and *e*, a connection *h* between the outer contact-arm of the relay 11 and the magnet of the relay 12, a connection *g* between the armature-bar of the relay 12 and the bell through a battery and a connection *g* between the inner contact-arm of the relay 12 and said bell, substantially as specified.

JOSEPH E. STEELE.
